UNITED STATES PATENT OFFICE.

LAMY A. GAUME, OF DANVILLE, KANSAS.

DISK-SLED ATTACHMENT.

1,159,660.

Specification of Letters Patent.

Patented Nov. 9, 1915.

Application filed February 7, 1914. Serial No. 817,205.

To all whom it may concern:

Be it known that I, LAMY A. GAUME, a citizen of the United States, and a resident of Danville, in the county of Harper and State of Kansas, have invented certain new and useful Improvements in Disk-Sled Attachments, of which the following is a specification, reference being had to the accompanying drawings, forming a part of this specification.

This invention relates to improvements in disk sleds and comprises an automatic attachment by means of which the soil, in the use of the disk sled, is cross harrowed, the furrows made by the disks being immediately closed while the ground is leveled, thus conserving the moisture, while eliminating the furrows.

Another object is to provide a disk sled with a time and labor saving attachment, that can be readily secured to a disk sled, expediting the working of corn, Kafir, cane, cow peas, or any other listed work.

With these and other objects in view, the present invention consists in the combination and arrangement of parts as will be hereinafter more fully described and finally pointed out in the appended claims, it being further understood that changes in the specific structure shown and described may be made within the scope of the claims, without departing from the spirit of the invention.

In the accompanying drawings forming a part of this specification, and in which like numerals of reference indicate similar parts in the several views: Figure 1 shows a side elevation of a disk sled provided with my attachment, the leveling knives being shown out of working position in dotted lines. Fig. 2 is a top view of Fig. 1. Fig. 3 is a side elevational view showing the tension lever thrown into working position. Fig. 4 is a view showing in detail one set of knives and their connections, a broken portion of the rock shaft also being shown. Fig. 5 shows an enlarged sectional detail of the two part tension spring. Fig. 6 shows a broken detail disclosing the members securing the tension lever to the tension bar. Fig. 7 shows a broken detached detail of one of the bearing ears and collars.

In my present invention I provide an automatic disk sled attachment, comprising a set of spring held drag knives, the position of which can be accurately adjusted and

which are carried by a holder the tension of which can also be adjusted and regulated so that where a field is worked comprising a dry, tough, cloddy heavy gumbo soil, the knives are held more stiffly than where used in light, mellow, moist loose or sandy soil. The knives operate to level the soil immediately after the passage of the disks so that there is no loss of moisture, and this leveling of the soil prevents washouts and the packing of the soil through rain.

In the drawings the numerals 1, 1 represent two suitable sled runners to the forward ends of which are secured the side bars 2, 2 by means of the bolts 3. Secured near the rear end to each runner 1 by means of a bolt 4 are the ends of the U-shaped frame 5 this frame being further braced by means of the brace bars 6 secured by means of the bolts 7 and 8. A seat *x* is fixed to this frame 5.

As shown in Fig. 3, each side bar 2 is provided with a U-shaped shackle 9, suitably secured thereto, and held upon the upper edge of each bar 2, by means of a shackle 9 is a disk shaft 10, provided with suitable cutting disks 11. At their inner ends these disk shafts 10 are connected to a bolt *a*, from which extends the connecting rod 12.

Held upon the upper edges of the side bars 2 is the cross bar 13 which is secured by means of the clips 14 which engage the bars 2, as shown in Figs. 1 and 3. Secured to this cross bar 13, is a gear sector 15 carrying a pivot pin 16 giving support to the operating lever 17 which is connected by means of the pin 18 to the connecting rod 12. By means of this lever 17 the disks 11 are adjusted. This lever 17 is provided with a suitable detent as is usual in lever construction, the detent being arranged for co-action with the gear sector 15. Further secured to the cross bar 13 is the gear sector 20 to which is operatively connected the adjusting lever 21 having a suitable detent or thumb latch arranged for co-action with the gear sector 20. To this adjusting lever 21 is secured the connecting rod 22 which has its upper ends suitably secured to the U-shaped frame 5. Secured to this cross bar 13 is the draw bar 23 carrying a suitable ring *b*, at its end to which the draft animals are connected.

Secured to each of the side bars 2 by means of a bolt *c* are the apertured standards 25, and 25', the standard 25 at its upper

end having a slotted head 26. This standard is braced by means of the rod 27 secured by means of the bolt 28 to the upwardly curved end of the side bar 2, as clearly shown in Figs. 1 and 3. Secured to the rear upstanding end of each side bar 2 by means of a bolt 28 is a counter-part carrying bar 30 each having one end slightly curved as is shown in Figs. 1 and 3. At their forward ends these carrying bars 30 are secured by means of bolts h , to the standards 25, 25'. At its rear end each carrying bar 30 has secured to it a bearing ear 31 one of said ears being shown in detail in Fig. 7, and these bearing ears are arranged to revolubly receive the bearing collars 2', each having a stop shoulder 3'', and a set bolt 3'. Securely held within these bearing collars 2' is a square rock shaft 32 to which are secured in parallel spaced relation, but in staggered position the trailing knives A, A' and B, B'. As shown in Fig. 2 one of the carrying bars is secured to the end of the opposite side bar 2, by means of a connecting rod f .

As shown the knives A and A' which are positioned below the knives B, B' are shorter than the knives B and B', all of said knives being curved, the knives A and B curving in a direction however opposite the knives A' and B', as shown in Fig. 2. These knives are adjustably secured to the rock shaft. The knives A and A' are each secured to an offset knife holder 34 shown in detail in Fig. 4, and within the socket 35 of each holder 34 the knives are held by means of suitable bolts and nuts 5' and 6'. These bolts pass through suitable slots v , within both the holder and the knife, so that these knives are adjustably secured to their holder. Each holder 34 has a head 36 having a square opening to receive the shaft 32, the holders being secured by means of set bolts 3'. Held in spaced relation to the offset holders 34 are the holders 37 having the sockets 38 within which are held the slotted ends of the knives B, the bolts 5' and nuts 6' being used to adjustably hold these knives B to the holders 37 which are also provided with slots v , as shown in Fig. 4. The knives A and B curve in one direction, while the knives B' and A' curve in opposite directions, the two longer knives B, B' being held adjacent one another.

Secured to the rock shaft 32 is a crank arm 33 which is held to the rock shaft 32 by means of a set screw 3' and this arm 33 at its upper end carries a bolt 7' as shown in Figs. 1 and 3, and this bolt in turn gives pivotal support to the apertured tension lever 40 which is adjustably secured to the bolt 7'. Near what forms its inner end the bar 40 is provided with a stop head 41 having the lip e , which is arranged to engage over the connected tension bar 43, the head

41 having an operating handle 42 as clearly shown in Fig. 6. The tension bar 43 is pivotally secured to the lever 40 by means of the bolt 8' and this tension bar 43 at its forward end is provided with a slotted socket 44, within which is held a two part spring comprising the intertwining coils 53 and 54. Slidably held within the socket 44 is the end 9' of the tension rod 46 carrying a pin 47 sliding within the slot 45. This tension rod 46 at its forward end is adjustably secured to a bolt carried by the set lever 50 which by means of a bolt g , is pivotally connected to the standard 25. Slidably held within the slot of the head 26 is a bolt 59 which passes through the lever 50 and gives support to a wing-nut 51, so that by means of this bolt 59 and nut 51 the set lever 50 can be locked to the standard 25 in regulating the tension of the members 46, 43 and 40. The length of the springs 53 and 54 can be adjusted in screwing or unscrewing the members 53 and 54 toward or away from one another, thus regulating the tension of the spring.

In going to or from a field, the tension lever 40 is thrown out of engagement with the tension bar 43, thus permitting the knives being thrown upward into a vertical position, as shown in dotted lines in Fig. 1.

As shown the attachment is simple and inexpensive in construction, and both durable and efficient in operation, and the tension of the knives may be regulated with ease, accuracy and despatch to meet the condition of the soil.

Having thus described my said invention what I claim as new and desire to secure by U. S. Letters Patent is:

1. In a device of the character described, two carrying bars, a rock shaft carried at the end of said carrying bars, two sets of curved knives secured to said rock shaft each set of knives including an upper and lower curved knife secured in parallel relation and staggered position, and means to tensionally hold said rock shaft.

2. In a device of the character described, a standard, two carrying bars secured in parallel spaced relation, a rock shaft carried at the end of said carrying bars, two sets of knives secured to said rock shaft in parallel relation and staggered position, each set of knives curving in opposite directions, a crank arm secured to said rock shaft, and a tension rod extending from said standard and secured to said crank arm.

3. In a device of the character described the combination of two side bars, two standards secured to said side bars, two carrying bars secured in parallel spaced relation to said standards and side bars, a rock shaft carried at the end of said carrying bars, two sets of knives secured to said rock shaft, each set of knives including two blades held in parallel relation and staggered position, a crank arm

secured to said rock shaft, a tension lever secured near one end to said crank arm, a tension rod secured at one end to said standard, a tension bar secured at one end to said 5 tension lever, and a spring connecting said tension bar to said tension rod.

4. In a device of the character described, two side bars, standards secured to each side bar, a carrying bar secured to each 10 standard and side bar, a set lever secured to one of said standards, a rock shaft carried by said carrying bars, two sets of curved knives secured to said rock shaft each set of knives curving in opposite 15 directions each set of knives held in parallel relation and staggered position, a crank arm secured to said rock shaft, a tension lever pivotally secured to said crank arm, a tension rod pivotally secured to said set lever, 20 and a tension bar tensionally secured to said tension rod and said tension lever.

5. The combination in a device of the character described of two side bars, a standard secured to each side bar, a carrying bar 25 secured to each standard and connecting said bar, a set lever pivotally secured to one of said standards, a rock shaft carried by said carrying bars, knives secured to said rock shaft in parallel spaced relation, a 30 crank arm extending from said rock shaft,

a tension lever pivotally secured to said crank arm having an engaging lip, a tension rod secured to said set lever, a tension bar secured to said tension lever, and a spring connection uniting said tension rod to said 35 tension bar, said lip arranged to engage said tension bar, as and for the purpose set forth.

6. In combination, two side bars, a standard secured to each side bar, a carrying bar 40 secured to each standard and side bar, a rock shaft carried by said carrying bars, knives secured in parallel staggered relation to said rock shaft, a crank arm secured to said rock shaft, a tension lever pivotally 45 secured to said crank arm, a set lever secured to one of said standards, a tension rod pivotally secured to said set lever, a tension bar pivotally secured to said tension lever said bar having a slotted socket, a pin secured to said tension rod and sliding within said slot, and springs within said socket working against said tension rod, as and in the manner set forth.

In testimony whereof I affix my signature, 55
in the presence of two witnesses.

LAMY A. GAUME.
